172,213

ILLUMINABLE DISPLAY SIGN

Merle W. Banks, Duluth, Minn., assignor to Lakeside Plastics & Engraving Co., Duluth, Minn., a corporation of Minnesota

Application November 9, 1953, Serial No. 27,495

Term of patent 7 years

(CL. D1—12)

To all whom it may concern:

Be it known that I, Merle W. Banks, a citizen of the United States of America, residing in Duluth, in the county of St. Louis and State of Minnesota, have invented a new, original, and ornamental Design for an Illuminable Display Sign, of which the following is a specification, reference being had to the accompanying drawing, forming a part thereof.

In the drawing:

Fig. 1 is a top plan view of an illuminable display sign showing my new design.

Fig. 2 is a side elevational view of Fig. 1.

Fig. 3 is a front elevational view of Fig. 1.

Fig. 4 is a perspective view of an illuminable display sign showing my new design.

I claim:

The ornamental design for an illuminable display sign, substantially as shown.
